Thomas Utley

UNITED STATES PATENT OFFICE

THOMAS UTLEY, OF TUEBROOK, LIVERPOOL, ENGLAND

SHIP'S LIGHT

Application filed May 10, 1930, Serial No. 451,367, and in Great Britain May 13, 1929.

This invention relates to ships' lights and has more particular reference to those known as "pivoted lights" in which a glass holder is pivotally mounted within the main frame 5 that is secured to the ship's hull or other part so that it can be angularly moved about a diametrical or medial axis to open the glass holder to any desired extent. In such pivoted lights, the glass holder which is usually of 10 circular shape is provided with diametrically opposite pins or projections that fit in slots in the inner wall of a double walled or box-like frame or body so that it is capable of being slidably or axially moved away from 15 the seating against which it bears when closed, into a position where it is free to be angularly moved about the axis passing through the pins or projections.

A ship's light of the type or character referred to is shown in Letters Patent No. 539,315, and among the objects of the present invention may be noted that of providing a construction which will be free from certain objections that experience with the construction of such patent has shown to be incident thereto.

The object of the present invention is to provide an improved construction of this type of light that avoids the use of the aforementioned double walled or boxlike frame, which apart from being somewhat expensive to manufacture is open to the objection that it forms a space or receptacle in which water or foreign matter entering through the said 25 slots can collect or accumulate. The improved construction in addition to avoiding the objection above referred to, provides a more satisfactory bearing for the glass holder within the main frame or body so as to facilitate the sliding and angular movements, 30 whilst it also has the advantage that it is less expensive to manufacture.

According to this invention the main frame or body is so constructed that it comprises a 45 single wall which is provided with grooves or channels in its inner surface to receive trunnions or projections on the glass holder. The grooves or channels are shallow and comparatively wide and the said trunnions or projections which fit closely therein, are flat at their 50 ends and bear on the flat inner surfaces or bottoms of the said grooves or channels to provide a substantial bearing which facilitates the sliding or axial movement of the glass holder, and also the angular movement. 55

Further according to this invention the construction is such that the glass holder can be readily inserted in or removed from the main frame at the inboard side of the frame. The main frame is provided with an internal 60 flange or rim having a rubber seating against which an annular projection or the like on the glass holder is pressed to make a watertight closure, portions of this flange or rim adjacent to the inboard ends of the aforesaid 65 grooves being cut away to provide openings which are normally covered by detachable plates or strips each having a projection with a rubber seating that forms a continuation of the seating in the flange or rim on the frame. 70 By placing the glass holder in a position with its axis at right angles to that of the main frame, it can be inserted in the said openings so that its trunnions pass into the said grooves in the main frame, whereupon it can be angularly displaced about the vertical axis passing 75 through the trunnions, so that it can be brought into engagement with the rubber seating. The detachable plates or strips when fitted, complete the said flange and rubber 80 seating and secure the glass holder within the groove. In some cases the glass holder may be inserted in or removed from the main frame at the outboard side, for which purpose abutments or an abutment ring may be provided adjacent to the outboard ends of the said grooves. The grooves however may be so shaped at the outboard end as to limit the outward movement of the trunnions on 85 the glass holder. 90

In order that the said invention may be clearly understood and readily carried into effect, the same will now be described more fully with reference to the accompanying drawings, in which:—

Figure 1 is a front view of the inboard side of a ship's light according to the present invention.

Figure 2 is a vertical sectional view taken 100 on the line 2—2 of Figure 1.

Figure 3 is a plan view showing the glass holder on the fully open position.

Figure 4 is an enlarged fragmentary sectional view similar to that shown in Figure 2.

5 Figure 5 is an enlarged fragmentary sectional view taken on the line 5—5 of Figure 1.

Figure 6 is a fragmentary plan view.

Figures 7 to 13 are detail views hereinafter referred to.

- 10 A represents the main frame or body which as shown is constituted by a single wall or ring having a flange A' that is adapted to be secured to the ship's side or other part in any suitable or usual manner. Strengthening webs A² extend from the said flange to the inner or inboard end of the single walled frame A where a flange or rim A³ is provided, this rim being provided with a rubber seating A⁴ as shown more particularly in the 15 sectional views. B represents the glass holder in which the glass plate B' is held in any suitable or usual manner, the inboard side of the glass holder having an annular projection B² which can be forced against the rubber seating A⁴ in the rim A³ by means of swing bolts C on the glass holder engaging with pivoted lugs C' on the main frame as shown in Figures 1 and 2. Raised portions are provided at diametrically opposite parts of the 20 inner surface of the main frame A, and they are formed with shallow and comparatively wide grooves or channels A⁶ that extend from the inboard side of the frame A to the outboard side. The glass holder B is provided 25 with diametrically opposite trunnions or circular projections B³ which are of such diameter as to fit closely in the said grooves A⁶ to provide a sliding fit without any lateral movement, whilst the outer ends of the said 30 trunnions or projections are flat so as to rest or bear against the flat inner surfaces or bottoms of the grooves. In order to open the light, the glass holder B is slidably moved in an axial direction from the position shown 35 in Figures 1, 2 and 6 towards the outboard side of the glass holder, and upon the trunnions B³ reaching the outboard end of the grooves A⁶, the glass holder can be angularly displaced about the axis of the trunnions to 40 assume a position at right angles to the main frame as shown in Figure 3. The bearing afforded by the trunnions or projections B³ within the said grooves A⁶ enables the sliding or axial movement of the glass holder away 45 from or towards the seating A⁴ to be easily effected, and it also facilitates the angular movement of the glass holder about the vertical axis passing through the aforesaid trunnions. The glass holder can be inserted in 50 the frame at either the inboard side or the outboard side of the frame as both ends of the grooves A⁶ are normally open. Detachable stops or an abutment ring A⁷ are provided at the outboard ends of the grooves as 55 shown in Figures 2, 4 and 5 to close the latter 60

and thus prevent unrequired removal of the glass holder at this side. The said grooves may however be shaped as shown in Figure 9 so as to limit the outward movement of the trunnions and thus prevent withdrawal of the glass holder at the outboard side. In order to enable the glass holder to be inserted or removed at the inboard side, the rim A³ of the frame A carrying the rubber seating A⁴ is provided with openings A⁸ (see Figures 8, 9 and 10) adjacent to the ends of the grooves A⁶. These openings may be closed by means of plates D which can be secured to the face of the rim A³ by screws or other means, and are provided with projections D¹ that fit closely within the said openings A⁸ to complete the annular formation of the rim A³. The said projections D¹ are also provided with a portion of rubber D² or the like that forms a continuation of the rubber seating A⁴ in the rim A³. When the said plates D with the projections D¹ containing the rubber strips D² are removed, the glass holder, when placed in a position so that its axis is at right angles to the axis of the main frame can be withdrawn or inserted as the width of the openings are such as to permit of the glass holder passing through them. After the glass holder has been inserted so that the trunnions fit in the said grooves, it can be 95 swung on the vertical axis passing through the trunnions into the position shown in Figures 1, 2 and 6, and the plates D can be replaced so that the openings A⁸ are closed. The rubber seating for the glass holder is therefore completed and the latter can be moved or drawn against the said seating by the bolts C to provide a water-tight closure. For the purpose of retaining the glass holder in the fully open position pivoted retaining 100 pieces E are provided on the main frame so that they can be placed in a position to engage with the front and rear surfaces of the glass holder as shown in Figure 3. These retaining pieces E in the example shown are carried on the detachable plate or strip D that closes the opening in the rim A³ adjacent to the lower groove A⁶ and this plate or strip may also carry a pivoted catch piece F which is adapted to engage with a notched or slotted projection B⁴ on the inboard side of the glass holder so as to retain the latter in a fixed position a short distance away from the seating A⁴ to provide a small opening for 105 ventilating purposes. If desired, an additional catch may be provided to retain the glass holder in any desired angular position. A cover or deadlight may be fitted to the glass holder on the outboard side if required.

110 The subject matter of the present improvements differs from that of the earlier patent before referred to in that the grooves or guideways for the glass holder trunnions are formed entirely within the main frame, and 115

such channels or grooves are of substantially uniform width throughout the depth.

According to the earlier, patented, construction, the guides for the glass holder trunnions or pivot pins were extended outward from the main frame and were permanently closed at their outer ends. Also, such channels or grooves were of greater width at the portions remote from the glass holder 10 and the pivot pins or trunnions were provided with enlarged end portions which were received in such expanded portions of the grooves.

Experience with the arrangement shown 15 in the patent has shown that said undercut grooves, closed at the outer end, are easily clogged by sand or other material accumulating therein which interferes with the desired free movement of the trunnions and 20 glass holder.

By forming the trunnion or pivot pin guides between two raised portions or ribs on the inner surface of the frame and making such pins or trunnions of substantially uniform 25 diameter throughout their length, this objection is avoided.

What I claim and desire to secure by Letters Patent of the United States is:—

1. A ship's light comprising a main frame 30 having grooves or channels formed on its inner surface and provided with an internal flange having a rubber seating in one face, said flange being provided with openings adjacent the ends of said grooves or channels, 35 a glass holder having trunnions fitted in said grooves or channels so as to be capable of sliding and angular movement therein, and closing plates provided with rubber pieces adapted to fit in the openings in the flange 40 so that the rubber pieces form a continuation of the rubber seating in the flange.

2. A ship's light comprising a main frame having raised portions on its inner surface spaced to provide grooves or channels which 45 are normally open at both ends, and having an internal flange adjacent its inboard end forming a seating for a glass holder, said flange having openings adjacent said grooves or channels, a glass holder having trunnions 50 slidably and pivotally fitted in said grooves and channels, closing plates having portions fitting said openings to provide a continuation of said flange, retaining bolts on the holder, and lugs on the main frame adapted 55 to be engaged by said bolts to retain the holder against the said seating.

3. A ship's light comprising a main frame having raised portions on its inner surface spaced to provide grooves or channels, which 60 are normally open at both ends, and having an internal flange at its inboard end forming a seating for a glass holder, said flange having openings therein adjacent said grooves or channels, a glass holder having trunnions 65 or projections slidably and pivotally mount-

ed in said grooves or channels, closing plates having portions fitting said openings in the flange to provide a continuation of the flange and seating, retaining bolts on the glass holder, lugs on the main frame adapted to be engaged by said bolts to retain the glass holder against said seating, spaced retaining members on one of said closing plates to engage the glass holder to retain it in fully open position, a pivoted catch piece mounted on 70 said closing plates, and a slotted lug on the glass holder adapted to engage said pivoted catch piece to retain the holder slightly separated from its seating.

4. A ship's light comprising a main frame 80 having on its inner surface within the marginal edges of the frame oppositely disposed, relatively wide and shallow grooves or channels with straight sides, and a glass holder movable axially and angularly in said frame 85 and having short trunnions or pivot pins of circular form in cross section and of substantially the same diameter throughout their length, fitting slidably and angularly in said grooves or channels without projecting through the frame.

5. A ship's light comprising a main frame 90 having integral raised portions on its inner surface forming between them straight flat-sided grooves or channels within the marginal edges of the frame, and a glass holder having short trunnions or projections extending therefrom and received in said grooves or channels.

6. A ship's light comprising a circular main frame, two pairs of spaced integral ribs on the inner peripheral surface of said frame, in substantially diametrically opposite relation with flat sides and a flat surface between them, and a glass holder having short 100 trunnions projecting therefrom into the flat-sided and flat-bottomed grooves or channels formed between said ribs whereby the holder is adapted to be slidably guided by said flat sides and flat surface of the grooves and 105 wherein it can be adjusted angularly with relation to the frame.

7. A ship's light comprising a main frame having a pair of substantially oppositely disposed grooves or channels on its inner surface within the marginal edge of the frame, the bottoms and sides of said grooves being flat, and a glass holder having trunnions extending into and slidably in said grooves or channels, said trunnions being of the same 115 diameter throughout their length with flat ends that can bear on the flat bottoms of the grooves or channels, and being guided whilst slidably or angularly moved by the flat sides of the groove.

8. A ship's light comprising a main frame having relatively shallow grooves or channels formed on its inner surface within the marginal edge of the frame, and having an internal flange that forms a seating, which is 120 125 130

- cut away adjacent the ends of said channels, a glass holder within said frame provided with opposite trunnions or projections extending into said grooves or channels without projecting through the frame, and means for closing the openings in said flange or seating after the glass holder trunnions or projections have been inserted in the grooves or channels.
9. A ship's light comprising a main frame having flat, shallow grooves or channels on its inner surface within the marginal edge of the frame, a glass holder having flat, shallow trunnions fitting in said grooves or channels so as to be capable of sliding and angular movement therein, said grooves or channels having flat, straight guiding sides and a flat bottom, and retaining members on the main frame adapted to engage with the front and rear surface of the glass holder to retain the latter in the fully open position.
10. A ship's light comprising a main frame having flat, shallow grooves or channels on its inner surface within the marginal edge of the frame, a glass holder having flat, shallow trunnions extending into said grooves or channels so as to be capable of sliding and angular movement therein, said grooves or channels having flat, straight guiding surfaces and a flat bottom, a seating on said frame against which the glass holder bears and a pivoted catch device on the frame adapted to engage with a slotted part on the glass holder to retain the latter in a fixed position spaced slightly from its seating.
11. A ship's light comprising a main frame having oppositely disposed grooves or channels on its inner surface, and provided with an internal flange adapted to form a seating for a glass holder, a glass holder having short trunnions extending into said grooves, means for retaining the glass holder against the seating, the internal flange being provided with openings to permit of the glass holder trunnions entering said grooves or channels, and closing plates fitted in said openings, one of said plates carrying retaining members adapted to engage the glass holder to retain it in an open position.
